EDWARD S. CRADDOCK, OF NEW YORK, N. Y., ASSIGNOR TO JOHN A. BOYAJEAN, OF JERSEY CITY, NEW JERSEY.

PILE FABRIC.

1,208,101.

Specification of Letters Patent. Patented Dec. 12, 1916.

Application filed April 16, 1915. Serial No. 21,728.

To all whom it may concern:

Be it known that I, EDWARD S. CRADDOCK, a citizen of the United States of America, and residing at New York, in the county of New York and State of New York, have invented new and useful Improvements in Pile Fabrics, of which the following is a specification.

This invention relates particularly to the heavier fabrics, such as rugs and carpets.

One object of the invention is to secure a close, compact weave.

Another object is to provide a structure which can be produced rapidly and economically.

According to this invention the pile warps are arranged in sets, the pile units of one set being looped over certain weft threads of the structure with intervening weft threads between them and the pile units of a different set being looped over said intervening weft threads. This binds the structure together and produces a close substantial fabric. Binders are woven in with the weft threads and pile units to give body to the fabric and to assist in locking the members together.

Other features will appear as the specification proceeds.

The accompanying drawing illustrates the invention as embodied in several preferred forms, but it will be understood that other changes and modifications may be made without departing from the true spirit and scope of the invention.

Figure 1, is a perspective view on an enlarged scale of a small portion of fabric embodying the invention in a simple form, the threads constituting the structure being shown separated for the sake of clearness. In this construction a single binder separates two sets of pile from the adjoining two sets and the binders are interwoven with the weft threads and the weft threads are interwoven between the binders and the pile warps. Fig. 2, is a like view of a slightly modified form wherein a single binder separates adjoining sets of pile and the weft threads are interwoven with the binders. Fig. 3, is a perspective view of another form wherein a pair of intertwined binders separate each two sets of pile from the adjoining sets. Fig. 4, is a similar view of a slightly different form wherein a pair of intertwined binders separate adjoining

sets of pile. Fig. 5, is a perspective view of a form wherein the binders loop over and under pairs of weft threads.

The body or base of the fabric is made up of wefts or weft threads and binders or warp threads combined in various ways. The pile warps are arranged in two parallel longitudinally extending sets, the units of such sets as cut apart by the pile wires of the loom, being designated 7 and 8 respectively. The units of one set, units 7 for instance, are looped over certain wefts 9 and up around the cross warps 10 at opposite sides of the looped-over wefts 9, and they are separated from each other by an intervening weft 11. The units 8 of the other pile set are looped over these intervening wefts 11, between the units of the first set and up around the wefts 10 at opposite sides thereof. The units of the second set 75 thus pass up around opposite sides of the same wefts which are looped about by two adjacent units of the first set. This alternating arrangement of the pile units as clearly illustrated in the different views 80 serves to tie the wefts together. The upright ends 12 of the pile units constitute the wearing surface and form when the structure is closely woven, as it will be in practice, a firm, durable fabric. 85

The binders are designated 15 in Fig. 1. These binders extend longitudinally of the fabric alongside of and parallel to the pile warps, and in this particular case each two sets of pile warps are separated by a single binder. 90 Also here, the binders while interwoven with the wefts are all parallel to each other.

In Fig. 2 I have shown how the individual sets of pile units 7 and 8 may be separated by single binders 17. The binders in this case are not parallel, alternate binders interlacing to opposite sides of the cross warps. This produces a somewhat heavier 95 and firmer structure than the first form. 100

The interposed binders may be arranged in pairs, as indicated in Figs. 3 and 4. In Fig. 3 there is a pair of intertwined binders 19 separating each two sets of pile units 105 from the adjoining two sets of pile units.

In Fig. 4, the individual sets of pile are separated by double intertwined binders 20.

The form shown in Fig. 5 is similar to that illustrated in Fig. 2, with the exception 110 that the binders 22 here loop over and under

pairs of wefts instead of single wefts, as in the preceding cases. This tying the weft threads together in pairs locks the pile units very firmly in place.

- 5 Different effects can be produced by varying the relative tensions on the weft threads and binders. Thus in Fig. 2, where the wefts are placed under greater tension than the binders, the wefts will remain relatively straight while the binders will be more or less sinuous. A reverse effect could be produced by reversing the tensions, making the tension on the binders greater than the tension on the weft threads.
- 10 The fabrics produced according to my invention are relatively simple and so can be produced rapidly and economically on a comparatively simple loom construction free of any particular complications. The parts of the fabric are all firmly united and tied together and form a durable, lasting structure.

A special feature, it will be noted, is that each pile unit of one set serves to tie together two adjoining pile units in the other set, each pile unit in a set being looped about the same two wefts which are looped about by adjoining pile units in the other set. The pile units being thus in effect tied together through the intermediacy of the wefts, act in the nature of binders and so give added longitudinal strength to the fabric. This binder effect of the pile units enables the use of smaller binder threads and this of course enables the pile tufts to lie closer together and so form a firmer and more compact fabric. Another important result of this construction is that at no point of the fabric are adjoining tufts separated by more than a single weft. The tufts thus lie close together and form a compact firm mass. Furthermore inasmuch as the tufts are not separated at any point by more than a single intervening weft the fabric is of uniform texture. This uniformity of texture provides a continuous interlocking of the pile units in all directions and so prevents the pile units working loose or being pulled out.

45 50 What I claim is:—

1. A pile fabric comprising wefts, a set of pile units looped over certain of said wefts and up around wefts at opposite sides of said looped-over wefts, adjacent pile units of said set being separated from each other by only a single intervening weft and a second set of pile units looped over said single intervening wefts between the units of the first set and up around the wefts at oppo-

site sides thereof which are looped about 60 by adjoining units in the first set of pile units, whereby each pile unit of one set serves to tie together two adjoining pile units in the other set and whereby adjacent upstanding tufts of the pile units are separated only by a single intervening weft to thereby form a close uniform firm pile structure.

2. A pile fabric comprising wefts, binders combined with said wefts and pile units 70 arranged in two sets, the pile units of the respective sets being looped over alternate wefts and under and up around the wefts between said looped-over alternate wefts, each pile unit in each set being looped over 75 a weft between adjoining pile units in the other set and up around the same wefts which are looped about by the adjoining units in the other set and thereby tying together the adjoining pile units in the other 80 set and providing in effect a substantial continuity of the pile units.

3. A pile fabric comprising wefts, a set of pile units looped over certain of said wefts and up around wefts at opposite sides 85 of said looped-over wefts, adjacent pile units of said set being separated from each other by only a single intervening weft and a second set of pile units disposed alongside and immediately adjoining the first set of 90 pile units and looped over said single intervening wefts between the units of the first set and up around the wefts at opposite sides thereof which are looped about by adjoining units in the first set of pile units, whereby 95 each pile unit of one set serves to tie together two adjoining pile units in the other set and whereby adjacent upstanding tufts of the pile units are separated only by a single intervening weft to thereby form a close 100 uniform firm pile structure.

4. A pile fabric comprising wefts, pile units arranged in two sets, the pile units of the respective sets being looped over alternate wefts between said looped-over alternate wefts, each pile unit in each set being looped over a weft between adjoining pile units in the other set and up around the same wefts which are looped about by the adjoining 110 units in the other set and thereby tying together the adjoining pile units in the other set and providing in effect a substantial continuity of the pile units and a single binder disposed between certain of the adjacent sets 115 aforesaid.

EDWARD S. CRADDOCK.
